CLAIM

(56) **References Cited**

The ornamental design for a shopping basket, as shown and described.

DESCRIPTION

FIG. 1 is a front perspective of a shopping basket with a second type of removable panel mounted on the front and the extendable handle in the stored position, the shopping basket being shown with wall openings in the left side, right side, front and rear walls,

FIG. 2 is a front view thereof,

FIG. 3 is a right side view thereof, the left side view thereof being a minor image of the right side view,

FIG. 4 is a top view thereof,

FIG. 5 is a rear view thereof,

FIG. 6 is a bottom view thereof; and,

FIG. 7 is a rear perspective view thereof with the extendable handle in the extended position.

The broken lines shown do not form part of the claimed design.
